UNITED STATES PATENT OFFICE.

HENRY J. COLE, OF GAINESVILLE, TEXAS.

RAIL-TIE.

1,316,354.

Specification of Letters Patent. Patented Sept. 16, 1919.

Application filed November 7, 1918. Serial No. 261,574.

To all whom it may concern:

Be it known that I, HENRY J. COLE, a citizen of the United States, residing at Gainesville, in the county of Cooke and State of Texas, have invented certain new and useful Improvements in Rail-Ties, of which the following is a specification.

This invention is a rail tie and has for its principal object the production of improvements in metallic structures of this nature.

One object of this invention is the production of a metallic tie which consists of a pair of similarly constructed sections which fit upon each other in such manner as to firmly engage the bases of two rails, for firmly holding the same against spreading and to properly support the rails.

Another object of this invention is the production of a rail tie, wherein the two sections are provided with lugs, whereby the lugs extending in opposite directions will engage the bases of two rails for holding the rails against spreading or slipping, while the bodies of the sections bear upon each other, and are provided with bases at their lower edges, thus causing the two sections to reinforce each other, whereby the rails will be firmly supported.

One practical form of construction and assembly of the present invention will be hereinafter described and is illustrated in the drawing, in which

Figure 1 is a side elevation of the rail tie, as constructed in accordance with the present invention.

Fig. 2 is a section taken on the line 2--2 of Fig. 1.

Fig. 3 is a section taken on the line 3--3 of Fig. 1.

Fig. 4 is a section taken on the line 4--4 of Fig. 1, and

Fig. 5 is a detail perspective view of one of the sections of the tie.

In the preferred embodiment of the present invention, about to be described, it will be seen that both sections are similarly constructed and by referring to Fig. 1, the construction of both sections will be fully understood. Each section comprises an elongated body 10 having a base 11 formed upon its lower edge and extending to a point adjacent its center from the outer end of the body. Thus it will be seen that the base 11 of the section is approximately one-half the length of the body. Furthermore, the base 11 extends beyond

one side surface of the body 10, for purposes to be hereinafter set forth.

A rail engaging flange 12 is formed upon the body 10 at one end thereof and the end 60 of the body and the upper surface of the lug 12 are beveled to form rounded outer portions 13. The inner edge of the lug 12 is beveled as indicated at 14 to conform in contour to the shape of the base of the rail, 65 for it will be noted that adjacent the beveled surface 14 of the lug 12, the upper edge of the body is flat, as indicated at 15 to allow a rail to rest evenly thereon. It will be noted however, that the lug 12 projects beyond one side surface of the body 10 in the same direction, as the base 11. The upper edge of the body 10 extends upwardly as indicated at 16 from the supporting surface 15 to form the lug 17 having a beveled 70 rail engaging surface 18. The under surface of the lug 17 is beveled to slant upwardly at one end, as indicated at 19 to correspond with the slanting surface 16 of the other section when the device is in use, as 75 will presently appear.

The body 10 is provided with a flat supporting surface 20 extending beyond the beveled surface 18 of the lug 17 and then the body 10 is curved downward, as indicated in 80 general at 21 to the base 11 thereof. It will be noted that the body 10 is provided with a central opening 22 intermediate its ends.

As above explained, two sections are used in the construction of the tie and they are 85 similarly constructed.

Therefore, the two rails to be supported by the tie, not being deemed necessary to be herein illustrated, are engaged by the two sections of the tie, which are at this 90 time spaced apart. Then by sliding the two sections toward each other, it will be seen that the bodies 10 will be brought into engagement with each other.

As above explained, the flange 12, lug 17 100 and base 11 of the section illustrated in Fig. 5 project beyond one side surface thereof and for this reason when the bodies of two sections bear upon each other, they will fit over corresponding edges of the remaining 105 section. The base of one section will fit under the body of the remaining section where the base of the remaining section does not extend, thus causing the two bases to extend throughout the entire length of the 110 tie.

As the flange 12 and lug 17 of one section

extend beyond the top edge of the opposite section, it is obvious the flanges 12 of the two sections extend in opposite directions, as do the lugs 17, as shown clearly in Fig. 5 1. Therefore, the bases of two rails will be gripped between the flange of one section and the lug of the remaining section at each end of the tie, thus causing the rails to be firmly held against spreading under any 10 conditions.

At this time, the bolt 23 is passed through the openings 22 of the bodies 10 and a nut 24 is applied to the bolt for firmly holding the two bodies in binding engagement with 15 each other.

It will therefore be seen that the rails will be supported upon the flat surfaces 15 and 20 of the two bodies and will be gripped by the lugs and flanges, thus being firmly supported and also be held from spreading under any conditions. Also, the manner in 20 which the bases of the two bodies fit under the bodies while the lugs and flanges overlap the edges of the bodies, the sections 25 will firmly reinforce each other and thus the tie will be firmly held against disassembly. Accordingly, when in use, the rails will be firmly supported, while it is only necessary to provide a bolt at the center of 30 the tie, for holding the entire device in an assembled condition, thus eliminating the necessity of spikes, or other retaining means, while the arrangement of the lugs and flanges are such as to eliminate the necessity 35 of gaging the distance between the rails, since they will be properly spaced apart by the spacing action of the lugs and flanges when the two bodies are being connected together.

40 The foregoing description and the drawings have reference to what may be considered

the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by 50 Letters Patent is:—

In a rail tie, the combination of a pair of similarly constructed sections, each section comprising an elongated body having a flat inner surface, a base formed on the lower 55 edge of said body and extending beyond the inner side thereof, said base being approximately one half the length of said body, said body having a rounded end merging into a wedged shape rail engaging flange 60 projecting beyond the inner side of said body, said body having a flat upper edge beyond said flange, thus forming a rail supporting surface, the edge then slanting upwardly and merging into a wedged shape lug, 65 whereby the rear portion of the lug will be reinforced, said edge then being flat beyond said lug and then terminating in a downwardly beveled end, whereby when the two sections are assembled they will fit upon 70 each other, while the lugs of the sections will be reinforced and the edges of the body which reinforce said lugs will tend to hold the rails on the surfaces in front of said flanges.

75 In testimony whereof I affix my signature in presence of two witnesses.

HENRY J. COLE.
